VENDING MACHINE

Harold Thomas Probasco, Inglewood, Calif., assignor to Oak Manufacturing Company, Inc., Los Angeles, Calif., a corporation of California

Application April 27, 1950, Serial No. 158,468

3 Claims. (Cl. 222—348)

1

This invention relates in general to vending machines for dispensing articles in measured quantities and partaking of the broad characteristics of the apparatus described in my application filed November 13, 1948, Serial No. 59,798 now Patent No. 2,537,317 issued January 9, 1951, but having for a particular object the provision of an article vending machine embodying novel improvements in and associated with the dispensing means for uniformly limiting the numbers or quantities of articles dispensed in successive operations especially when the dispensable articles are solid, hard, irregular as to size and form and are in the form of charms or novelties pleasing to children.

In the consideration of the present improvements over the apparatus disclosed in my said pending application for patent it may be understood that said prior apparatus was structurally designed to freely dispense measured quantities of products such as nuts, chewing gum, candy and other crushable foods, whereas, the present invention is effective for adapting the apparatus of said prior application for patent for dispensing firm, solid or hard articles of small but different size and of different form, with equal facility, in substantially uniform number or quantity and without injury to the dispenser or to the dispensed articles, and without retarding or clogging the dispensing mechanism.

Hence, this invention is restricted to the dispenser and associated mechanism independently and in combination and an object is to provide in a vending machine for the purpose described embodying a rotatable pocketed dispenser, and a stationary article holder superposed on and under which the dispenser rotates, whereby articles are delivered to a plurality of pockets in the dispenser and are moved in an arcuate path toward an outlet, and detent means at a fixed point in the movement of the dispenser which when engaged by the articles will yield to accommodate the movement thereunder of articles of different size and contour and yet obstruct the movement of over-sized or surplus articles to dispensing position.

In my said prior application for patent I disclosed a well known form of detent means for preventing the over-dispensing of a predetermined quantity of articles which were resilient and yieldable by pressure of approaching articles thereagainst as the dispenser is rotated and including a series of closely wound brushes fixed at their upper ends to a common support and free at their lower ends to yield so as not to

damage the products moved thereunder in a dispensing operation, but in such case the dispensable articles were of substantially uniform size and character, whereas in the instant case the articles may be of various size, character and form, and it is, therefore, an object to provide a detent means which includes a plurality of resilient elements individually and independently yieldable not only in the direction in which the articles move toward dispensing position, but also upwardly from the plane of the articles. Other objects may appear as the description of my present improvements progresses.

I have shown a preferred form of mechanism embodying my invention in the accompanying drawing, in which

Fig. 1 is an elevational view, partly in section, of a vending machine showing the application of my present improvements thereto;

Fig. 2 is a plan view of the dispensing unit on line 2—2 of Fig. 1 with the container removed;

Fig. 3 is a perspective view of a stationary fixture disposed above a rotatable dispensing element and including yieldable elements for leveling the contents of the pockets in the dispensing element and preventing more than predetermined quantities of the dispensable articles from being dispensed from the machine;

Fig. 4 is a fragmentary elevational view of the stationary and movable dispensing elements showing how the resilient detents yield in one direction to permit passage of flat articles therebeneath;

Fig. 5 is a view of the dispensing element showing how the detents yield in two directions to permit passage therebeneath of relatively larger articles of similar or different form and size; and

Fig. 6 is a fragmentary sectional view of the yieldable detents on line 6—6 of Fig. 4.

While my present improvements as shown in the several views of the drawing are capable of use in several types of vending machines, I have shown and will describe my said improvements as when adapted to a machine of my invention as disclosed in my said pending application for patent.

As shown, said machine includes a base A, a housing B superposed on such base, a member C superposed on said housing, a container D borne by member C for holding a quantity of dispensable articles, a top E borne by container D, and a rod F fixed to base A and top E at opposite ends and extending through members

B, C and D for securing said several parts together.

Member C forms a support for a multiple pocketed rotatable dispensing element G which is disposed horizontally on the bottom 1 of a well 2 and has a central hub 3 which seats on a central boss 4 of bottom 1 and is adapted for rotation as by means of an external knob 5 fixed to a shaft 6 which bears a gear 7 held in mesh with suitable gear teeth 8 or corresponding apertures in a peripheral portion of element G, or otherwise not material to this invention. Operating shaft 6 may be supported in the front wall 9 of housing B or in a fixture 10 borne by wall 9 and capable of supporting a suitable coin operated unit for controlling operation of dispenser G.

Bottom 1 of member C has an aperture 11 therein with which pockets 12, 12 etc. of dispenser G successively register as dispenser G is rotated. Pockets 12 are spaced apart by segments 13, 13, etc. having webs 13' in a common horizontal plane and said pockets are open both at their tops and bottoms so that they may receive changes of articles a, a, etc. (Figs. 4 and 5) from the interior of container D and when moved into registration with aperture 11, discharge the articles into and through a chute 14 for delivery at an external mouth 15 to a user when a closing flap 16 is opened.

The mechanism so far described is not a part of the present invention but associated with my new improvements in an interdependent relationship which will be readily understood by the ensuing description of the new improvements.

A frusto-conical member 17 is mounted on housing member C at an annular flange 18 which is notched at points 19, 19 to embrace pins 20, 20 borne by an annular portion 21 of member C, for holding member 17 against rotation. A fixture H of the character best shown in Fig. 3 is mounted in and secured to member 17 as by means of two or more screws or pins 22 extended through apertures 22' in a substantially semicircular top plate 23 for positively holding the fixture against rotation.

Plate 23 has a diametrically disposed margin 24 extended inwardly from the arcuate margin 25 thereof to a point slightly beyond the common axis of members G and 17 and depending portions 26 and 27 in a common radial plane so as to dispose the lower edges 26' and 27' of said depending portions in a horizontal plane slightly above the webs 13' of the segments 13 of dispenser G. Thus, there is provided a space 28 between portions 26 and 27 of a radial length substantially corresponding to the radial dimension of the pockets 12 of dispenser G so as to permit movement of the articles therethrough.

Plate 23 is formed with a recess 29 between portion 27 and a segment 30 and substantially corresponding in position to space 28, within which a plurality of resilient detents 31 are suspended in radial alignment from similar arms 32 which are coaxially pivoted to plate 23 on a pin 33 borne at opposite ends by depending flanges 34 and 35 of plate 23 at opposite margins of recess 29.

Said detents are formed of closely wound steel springs which are anchored at their upper coils to the free ends of arms 32 and are of sufficient length and tension that when mounted as shown in the path of the articles in pockets 12 of the dispenser, they will yield by pressure of the

articles thereagainst so as to permit passage of a normal quantity of articles therebeneath but will prevent passage of a surplus of articles and thereby normalize or measure a predetermined quantity at each operation of the dispenser.

It will be understood that when the dispensable articles are of uniform size and character and especially of relatively small size, the detents 31 do not necessarily flex but merely serve to scrape the top of the dispenser and push back or prevent the passage of more than a predetermined quantity of articles beneath the detents.

But when the articles are sufficiently large the detents yield to a substantial extent to permit passage of the articles thereunder. The extent to which the detents can yield when not borne by the arms 32 is limited even for use with articles of uniform size and it is desirable to extend the range of their usefulness to articles of uniformly maximum size as well as selectively to articles of various size; hence the provision of the arms 32 for affording yieldability of the detents upwardly as well as forwardly and without undue forward yielding of the detents. Thus, the detents are of inherent tension against forward yielding and the arms 32 are tensioned against upward yielding as by means of springs 38 which are intermediately coiled at 37 around pin 33 with their free ends 38 bearing against arms 32 and their other ends anchored at 39 to plate 23.

In operation, as the dispenser G is rotated for a fraction of a revolution necessary to move one of the article filled pockets 12 into registration with outlet 11 by turning handle or knob 5, the contents of such pocket will drop into and through chute 14 and lodge in mouth 15 where they are accessible to a user. In the meantime as the dispenser is so moved the contents of succeeding pockets 12 will be brushed by the detents 31 and surplus quantities thereof will be prevented from passage beneath the brushes although the brushes will yield forwardly and upwardly to a sufficient extent which will permit passage therebeneath of articles of different size, form and character.

In other types of vending machines the resilient detents have been rigidly anchored at their upper extremities and were of sufficient number to extend substantially across the dispenser and because the detents could not yield upwardly the apparatus was not of sufficient yieldability and selectivity as to permit passage under the detents of any but articles of substantially uniform size, form and character.

In the instant apparatus it is apparent that because the relatively few detents 31 are radially aligned in the path of the articles as the pockets approach discharging position instead of a greater number diametrically aligned across the dispenser, and further because the detents independently yield both forwardly and upwardly, the dispensing of articles which cannot be vended from other types of machines is not only possible but is effectively accomplished by a machine embodying my invention and without possibility of damage to the vended articles or parts of the machine.

I claim:

1. In a vending machine: the combination with a horizontally disposed rotatable dispenser formed with a shallow receptacle for receiving articles from a container thereabove, of a fixture formed with a horizontal web overlying a segment of said receptacle and having a recess in a portion thereof, a plurality of parallel arms of flat

cross section coaxially hinged to said fixture at their rear extremities and normally disposed flatwise of said web in said recess, means for individually tensioning said arms to urge their forward extremities downwardly, and separate coiled wire detents anchored at their upper ends to the forward ends of said arms in radial alinement over said receptacle, said detents being free to yield bodily below and upwardly with said arms when engaged by articles in said receptacle as the dispenser is rotated, so as to limit passage of articles thereunder and restrain passage of an excess number of articles in a dispensing operation.

2. In a vending machine: the combination as set forth in claim 1 in which said fixture has depending portions extended from the unrecessed section of said fixture with an opening therebetween to permit unrestrained passage of any

articles remaining in the receptacle after dispensing operation.

3. In a vending machine: the combination set forth in claim 1 in which said arms have tail portions underlying adjacent portions of said fixture to limit the downward thrust of said detents.

HAROLD THOMAS PROBASCO.
